UNITED STATES PATENT OFFICE

2,570,178

ELECTRIC ORGAN

Victor I. Zuck, Kenmore, N. Y., assignor to The
Rudolph Wurlitzer Company, North Tonawanda, N. Y., a corporation of Ohio

Application January 2, 1947, Serial No. 719,896

18 Claims. (Cl. 84—1.14)

1

The present invention pertains in general to electric organs and, in particular, to pallet structures and their associated parts in electric organs of the air-driven reed type, wherein the reeds are employed as generators to produce electrical signals which are amplified and then converted into acoustic waves by a loud speaker.

Each key of an organ is enabled to control the activation of any one of a number of different tone sources through the provision of stop tablets that determine which tone sources in a group associated with a particular key are activated in response to the operation of such key. In certain organ structures heretofore used, the stop tablets have been arranged to control shutters disposed in air passages extending between a wind chest and the organ reeds; or to control electrical circuits extending between a key operated switch and a number of electrically operated pallets each individual to a reed associated with such switch. Either of these methods of controlling the activation of particular tone sources in response to the operation of a key involves cumbersome, complex and costly apparatus which is not well adapted to many uses such, for example, as in a compact and inexpensive organ intended for home use.

It is an object of the present invention to provide an improved organ of the type described which is constructed in such manner as to greatly reduce the number of parts required for its manufacture without unduly limiting the tonal range thereof, whereby a very compact and inexpensive organ is provided, which is well adapted for use in the home.

A further object of the invention is to provide a simplified operating mechanism for the pallets of an organ to reduce the cost thereof, to minimize the amount of maintenance required, and to provide a delicate key touch and quick response through a reduction in the inertia of, and the frictional losses in, the pallet mechanism.

More specifically stated, an object of the invention is to provide an improved organ of the type described wherein the pallets are arranged to be directly operated by the organ keys in an improved manner, and are operative to control the activation of a group of reeds associated with the operated organ key; and wherein electrical pick-ups individually associated with each reed of the activated group may be selectively connected to an audio-amplifier system, under the control of the organ stop tablets, so that only desired ones of the activated reeds are effective to produce audible tones.

These and other objects of the invention will

2

best be understood upon a perusal of the following specification taken in conjunction with the accompanying drawings, wherein:

Fig. 1 is a diagrammatic side elevational view of an electronic air-driven reed organ incorporating the invention;

Fig. 2 is a schematic electrical diagram illustrating one manner in which the stop tablets of the organ shown may be employed to control the quality of the tones produced in response to the operation of the organ keys;

Fig. 3 is an enlarged transverse sectional view through the reed frame, wind chest, and keyboard of the organ shown;

Fig. 4 is a longitudinal sectional view of a portion of the reed frame and wind chest shown in Fig. 3, taken along the line 4—4 therein;

Fig. 5 is a fragmentary view in vertical section of the rear portion of the wind chest, showing a fastening device for the rear panel;

Fig. 6 is a plan sectional view taken on the line 6—6 in Fig. 4;

Fig. 7 is a vertical sectional view of the wind chest stripped of internal attachments;

Fig. 8 is a fragmentary elevational view of a modified key structure; and

Fig. 9 is a transverse section along the line 9—9 in Fig. 8.

The organ set forth for illustrative purposes in Fig. 1 is a single manual instrument having a keyboard 6, a set of stop tablets 8 disposed above the keyboard, a wind chest 10 located immediately behind the keyboard 6, a reed frame 12 disposed above the wind chest, an air compressor 14 which is coupled to the wind chest 10, and an audio frequency amplifier 16.

As will subsequently be described, circuit arrangements are provided for selectively connecting the amplifier electrically to different sets of reeds disposed in the frame 12 under the control of the stop tablets 8; the electrical tone signals developed by the selected set, or sets, of reeds being amplified and delivered to a loudspeaker for conversion into corresponding audible sounds.

The reed frame 12 extends lengthwise of the organ and contains rows of reeds disposed along its front, rear and upper sides. The organ cabinet preferably is provided with a hinged lid to permit ready access to be had to the reed frame 12.

Referring now in particular to Fig. 3, the keyboard 6 comprises a key frame 18 which extends lengthwise of the organ and has a plurality of spaced apart balance pins 20 extending vertically therefrom. Keys 22 are fulcrumed on felt washers 24 disposed around the balance pins 20,

which extend through openings in the keys. The keys are biased to pivot in a clockwise direction, as viewed in Fig. 3, by coil springs 26 which are secured at one end to adjustable screw eyes 28 extending through the keys, and are secured at their other ends to spring anchors 29 on the key frame 18. Clockwise movement of the keys 22 is limited by check screws 30 which extend through counterbored openings in the key frame 18 into the under sides of the keys, and the keys are guided at their forward ends by guide pins 32 which extend from the key frame 18 into clearance openings in the under sides of the keys 22.

A modified form of key structure utilizing metal weights 33 instead of springs 26 to restore the keys is shown in Figs. 8 and 9. The weights 33 carried by the rear portion of each key 22a replace the springs 26, eyes 28 and spring anchors 29.

Felt pads 34, Fig. 3, are secured to the upper sides of the keys at their rear ends where they engage plungers 36 which extend into the wind chest 10. The pads 34 are attached to flexible arm portions 38 of the keys 22, to enable adjustment of the pads relative to the body portion of the keys by means of adjusting screws 40. The plungers 36 extend through openings in the under side of the wind chest 10 and through a wind seal 41, which consists of an apertured, inverted channel running the full length of the row of plungers 36. The holes in the wind chest 10 and wind seal 41 through which the plungers 36 pass preferably are lined with felt or the like. The heads 42 of the plungers 36 are provided with felt pads on their upper sides where they engage corresponding pallets 44 at one end thereof.

Each of the pallets 44 corresponds to one of the keys 22. The pallets are fulcrumed on a quarter-round strip 46 which is secured to and extends lengthwise of a pallet board 48 forming the upper wall of the wind chest. The pallets are retained in position by guide pins 50 and 52, which extend from the under side of the pallet board through clearance openings in the pallets. The pallet board 48 is provided with a row of openings or ports 54 which normally are sealed by obturators 56 attached to the upper surfaces of the pallets 44. The obturators 56 may comprise felt pads which are faced with leather.

The pallets 44 are biased by springs 57, Figs. 3 and 4, to pivot in a counter-clockwise direction, as viewed in Fig. 3, so as to seal the associated ports 54. These springs 57 engage slots in the pallets 44 at one end and are anchored at their other ends in a wooden strip 58, which is secured to the under side of the pallet board 48. The wind chest 10 is provided with a removable rear cover panel 59 to enable access to be had to the pallet mechanism. The panel 59 is secured to the wind chest 10 by fastening devices shown in detail in Fig. 5. Bushings 60, internally and externally threaded, are screwed into suitable openings in the rear edges of the wind chest 10 and wooden strip 58. Screws 61 passed through the panel 59 are received by the internal threads of the bushings 60. Thus, a tight fit of the screws 61 is assured despite frequent removal and replacement of the panel 59. The inner face of panel 59 is covered by a layer of sound-absorbing material 62 which is a separable part of a sound-proof lining 63 extending over the inner surfaces of the wind chest 10.

It will be noted that there are only three moving parts in the pallet and pallet-operating mechanisms; namely, the keys, the pallets, and

the plungers linking the keys to the pallets. This small number of moving parts results in a pallet mechanism having low inertia and small frictional losses. The provision of substantially 5 knife-edge bearings for the pallets further assists in reducing the frictional losses to a very low value. This reduction in the inertia, and the frictional losses, of the pallet mechanism results in a very light and delicate key touch even though 10 the lever ratios of the keys and pallets are chosen so as to provide a quick response, that is, a considerable opening of the pallets in response to a small movement of the corresponding keys.

As one of the features of the present invention, 15 a plurality of reeds is arranged to be operated under the control of each pallet as 44. Thus, referring to Figs. 3, 4 and 6 there are provided, in this instance, three reed blocks 64, 65 and 66, each corresponding to a particular organ stop. 20 The reed blocks 64 and 66 are mounted on edge upon the pallet board 48 in opposed relation on either side of the ports 54 in the pallet board, these reed blocks extending lengthwise of the reed frame 12. The reed block 65 is mounted in 25 inverted relation above the reed blocks 64 and 66 in such manner as substantially to bridge the reed blocks 64 and 66. The reed block 65, as will be explained more in detail presently, is supported by a cell block 68 secured to the upper face of the pallet board 48.

Individual cells 70 are formed in the block 68 by a routing tool or in any other suitable manner, there being a cell 70 for each port 54. The cells 70 in the block 68 are respectively aligned with 30 reed cells 72 in the reed block 66. The walls of the cells 70 are cut back at their upper ends to accommodate a reinforcing strip 74 of substantially square cross-section which extends lengthwise of the cell block 68. The reed block 65 is secured to the upper face of the strip 74. Cells 76 are formed in the block 68 opposite the cells 70, from which they are separated by a central web or dividing panel 78 at the midportion of the block 68, which serves as a baffle. These 35 cells 76 are respectively aligned with reed cells 79 in the reed block 65. Another cell block 80 disposed on the pallet board 48 adjacent the cell block 68 has individual cells 81 formed therein which are aligned respectively with reed cells 82 in the reed block 64. The walls of the cells 81 are cut back at their upper ends to receive a square reinforcing strip 83 extending lengthwise of the cell block 80.

The foregoing arrangement affords communication from the ports 54 through the cells 70, 55 76 and 81, respectively, to the reed cells 72, 79 and 82 so that when the pallet 44 is open, air under pressure is directed from the wind chest 10 to the various reed cells for actuating the reeds 84 disposed therein. The walls of the reed cells 72, 79 and 82 are grooved to receive reed pouches 85 which carry the reeds 84, the heels of these reed pouches protruding from the reed blocks. Suitable apertures in the reed pouches 85 permit 60 the passage of air to the reeds 84.

In accordance with the general principles set forth in Hoschke Patent 2,015,014, dated September 17, 1935, the mechanical vibrations of the reeds 84 are employed to generate electrical signals by means of capacitative pick-up elements 86 which extend through openings in the reed blocks 64, 65 and 66 and terminate in plates 70 extending parallel to the reeds 84 and disposed near the free ends thereof. The pick-ups 86 are threaded through conductive strips 88, which 75

extend lengthwise of the reed frame 12 and are insulated from the reed blocks 64, 65 and 66 by means of insulating strips 90. The distances between the pick-ups 86 and the respective reeds 84 may therefore be adjusted by rotation of the pick-ups. Undesired movement of the pick-ups is prevented by means of lock nuts 92 threaded thereon. The reeds 84 and their pouches 85 are electrically conductive and connection therewith is established by means of metallic strips 94, which extend lengthwise of the reed frame 12 and are in contact with the heels of the pouches 85.

When any one of the keys 22 is depressed, it raises the plunger 36 associated therewith to effect clockwise movement of the corresponding one of the pallets 44, Fig. 3. Air is thus admitted from the wind chest 10 to the cells 70, 76 and 81 and is directed against the three reeds 84 corresponding to the operated key, thereby exciting this group of reeds simultaneously.

When one of the reeds 84 is activated, the capacity between such reed and the adjacent one of the pick-ups 86 undulates in a periodic manner to produce an electrical signal across a load connected thereto in series with a source of potential. The signal developed across the load has a waveform that is characteristic of the activated reed.

On passing beyond the reeds, the air emerges from the open ends of the reed cells 72, 79 and 82 and travels lengthwise of the reed frame 12 through passages defined by the reed blocks 64, 65 and 66 and covers 96, Fig. 3, and thence is exhausted through an exit port (not shown). The covers 96 are hinged at 97 to enable access to be had to the reed pouches 85 and are lined with pads 98 of sound-absorbing material as a barrier against the direct radiation of sound from the reeds. Unwanted leakage of sound from the various reed blocks is further suppressed by a sound-absorbing box-like structure 99 constructed of Celotex or similar material mounted on the pallet board 48 and enclosing the reed frame 12. Preferably the interior walls of the box 99 are provided with sound traps in the form of pits or indentations having a depth of more than half the thickness of the material and disposed at regular, short intervals over the whole interior surface thereof.

The reed frame 12 is covered by a shield 100 of sheet metal mounted on the pallet board 48 so that the pick-up circuits are not affected by stray magnetic fields. The base of the shield 100 is in contact with a metallic coating 101, Fig. 7, sprayed on the edge portions of the pallet board 48. The interior surfaces of the wind chest 10 are sprayed with molten metal to form a coating 102 which contacts the coating 101 when the sound-producing apparatus of the organ is assembled. (The sound-proof lining 63 and the pallet mechanism are not shown in Fig. 7.) Thus, the sound-producing apparatus comprising reed frame 12 and wind chest 10 is completely enclosed by a metallic shield which may be suitably grounded.

Referring now to Fig. 2, the sets of reeds 84 which are associated respectively with the reed blocks 64, 65 and 66 are designated RS1, RS2 and RS3, respectively. The reeds in each of these sets may be pre-voiced in any suitable manner, as by forming the reed tips, to produce characteristic tones such as flute, viola, and clarinet. All of the reeds 84 included in the same group, Fig. 3, are associated with a particular one of

the organ keys 22, and all such reeds are activated simultaneously by the operation of a single pallet 44 when the corresponding key 22 is operated. The pick-up elements 86 of all of the reeds 84 are connected in parallel to one of the input terminals 103, Fig. 2, of the audio-amplifier 16, the other one of the input terminals 103 being connected to ground. The reeds in each of the sets RS1, RS2 and RS3 respectively disposed in the reed blocks 64, 65 and 66 are connected in parallel and to a corresponding one of the group of switches ST1, ST2 and ST3 controlled by the stop tablets 8.

When the stop tablet switch ST1 is operated, the reeds included in set RS1 are connected to the negative terminal of a source of potential 104 having its positive terminal connected to ground. When one of the organ keys 22 is operated, a corresponding group of three reeds 84, which includes a reed in each of the three sets RS1, RS2 and RS3 thereof, will be activated. The activated reed in the set RS1 will be the only one in the group that is effective to produce an electrical signal across the input terminals 103 of the amplifier 16, since there is no polarizing potential applied to the activated reeds in sets RS2 and RS3. The audible signal produced by loud-speaker 105 connected to output terminals 106 of amplifier 16 will thus be characteristic of the activated reed in set RS1.

In a similar manner, if stop tablet switch ST2 is operated and the remaining switches are normal, the activated reed in set RS2 will be the only one that is capable of producing a signal voltage across terminals 103 when the organ key is operated, although all three reeds in the same group are activated simultaneously by the operation of the key.

Each of the switches ST1a, ST2a and ST3a operates in the same manner to impress a polarizing voltage on the corresponding set of reeds RS1, RS2 or RS3, but these switches are connected to a tap on the source of potential 104 whereby a lower signal voltage is developed across terminals 103 when one of these switches is operated than when the corresponding one of the switches ST1, ST2 or ST3 is operated. Thus, when more than one stop tablet is operated simultaneously, the two sets of reeds thereby made effective may have equal polarizing voltages impressed thereon, whereby they will be equally effective in producing signal voltages across terminals 103; or either one of the sets of reeds may have a lower polarizing voltage impressed thereon than the other set in order to combine the signal voltages developed in a predetermined manner.

It should now be apparent that, by reason of the novel constructional features disclosed herein, an organ has been provided which is very economical to produce and is very compact in size and hence is admirably suited for use in residences and other low cost installations. The simplification of the pallet action eliminates a great deal of needless friction, by minimizing the number of moving parts required, and greatly reduces the inertia of the pallet mechanism, thereby resulting in a light key touch. The lever ratios of the pallets and keys are preferably chosen to provide a quick response, which can only be obtained at the expense of a heavy key touch when more cumbersome pallet mechanisms are employed.

By reason of the provision of a pallet which is effective to control an entire group of reeds, any one or more of which may be made effective

to produce audible tones by the operation of corresponding stop tablets, the need for expensive and complicated coupler boards oftentimes employed in electric organs is eliminated, thus effecting a very great saving in cost and space.

While certain selected embodiments of the invention have been shown by way of illustration, it should be apparent that various modifications may be made therein without departing from the invention in its broader aspects, and therefore the aim of the appended claims is to cover all such modifications as fall within the true spirit and scope of the invention.

The invention is hereby claimed as follows:

1. In a reed organ including a horizontally extending row of reed cells, a pallet board disposed substantially in a horizontal plane and having ports therein respectively aligned with the reed cells, a row of individually operable pallets fulcrumed on the under side of said pallet board and respectively biased to close said ports, a horizontally disposed key frame, a row of keys fulcrumed on the upper side of said key frame, one end of each of said keys underlying and being vertically aligned with one end of a corresponding one of said pallets, and means coupling said keys respectively to said pallets whereby depression of the other end of any of said keys elevates said one end of the corresponding pallet to open its associated port.

2. In a reed organ including a horizontally extending row of reed cells, a pallet board disposed substantially in a horizontal plane and having ports therein respectively aligned with the reed cells, a row of individually operable pallets fulcrumed on the under side of said pallet board and respectively biased to close said ports, a horizontally extending key frame disposed at a lower level than said pallet board, a row of keys fulcrumed on the upper side of said key frame with one end of each said key disposed vertically beneath one end of a corresponding one of said pallets, and vertically shiftable plungers interposed respectively between the vertically aligned ends of said keys and said pallets, whereby depression of the other end of one of said keys elevates said one end of the corresponding pallet to open its associated port.

3. In a reed organ, a wind chest including a pallet board having a row of apertures therein, a plurality of pallets, each operative to control the flow of air through a corresponding one of said apertures, a plurality of reed blocks arranged to bridge the row of apertures in said pallet board, each of said reed blocks housing a row of reed cells perpendicularly disposed relative to each other and respectively opening toward said pallet board apertures, a plurality of walls dividing the space enclosed by said reed blocks and said pallet board into individual cells for establishing communication between said apertures and said reed cells, and a plurality of reeds respectively disposed in said reed cells, said other cell walls being so arranged that selected groups of reeds are activated in response to the operations of said pallets.

4. In a reed organ, a wind chest including a pallet board having a row of openings therein, a plurality of pallets, each operative to control the flow of air through a corresponding one of said openings, a pair of parallel spaced-apart reed blocks extending from said pallet board on either side of said row of openings, a third reed block perpendicularly disposed in respect to and bridging said pair of reed blocks, a plurality of

walls dividing the space enclosed by said three reed blocks and said pallet board into individual cells communicating with the openings in said pallet board, said reed blocks having openings therein communicating with said cells, and a plurality of reeds respectively disposed in the openings in said reed blocks, said dividing walls being so arranged that selected groups of reeds are activated in response to the operations of said pallets.

5. In a reed organ, a wind chest including a horizontally disposed pallet board having a row of ports therein, a plurality of reed blocks perpendicularly disposed and bridging the row of ports in said pallet board, a plurality of walls dividing the space enclosed by said reed blocks and said pallet board into individual cells communicating with said ports, said reed blocks having openings therein communicating with said cells, a plurality of reeds respectively disposed in the openings in said reed boards, a row of pallets fulcrumed on the under side of said pallet board and respectively biased to close said ports, said dividing walls being arranged to associate said reeds in groups respectively with said pallets, a key frame disposed horizontally, and a row of keys fulcrumed on the upper side of said key frame, one end of each said key being vertically aligned with and coupled to one end of a corresponding one of said pallets, whereby depression of the other end of any of said keys elevates said one end of the corresponding pallet to open its associated port thereby to activate all of the reeds in the group associated therewith.

6. In an electric organ, a plurality of reeds arranged in sets, means for vibrating said reeds selectively in groups, each such group containing a reed from each of said sets thereof, a source of electric current having high-voltage and low-voltage terminals, an amplifier, a plurality of individually operable first stop tablet switches adapted to connect said sets of reeds selectively in circuit with said high-voltage terminal and said amplifier, and a plurality of individually operable second stop tablet switches adapted to connect said sets of reeds selectively in circuit with said low-voltage terminal and said amplifier.

7. In an air-driven reed organ, a wind chest, a removable panel on said wind chest, and fastening devices for securing said panel to said wind chest, each of said fastening devices comprising a bushing having internal and external threads screwed into said wind chest, and a screw extended through said panel and adapted to be received by the internal threads of said bushing.

8. In a reed organ including a horizontally extending row of reed cells, a pallet board disposed substantially in a horizontal plane immediately adjacent the reed cells and having ports therein respectively aligned with the reed cells, a row of individually operable pallets fulcrumed on the underside of said pallet board, a horizontally disposed key frame, a row of keys fulcrumed on the upper side of said key frame, each of said keys having an end thereof underlying and vertically aligned with one end of a corresponding one of said pallets, means coupling said keys respectively to said pallets whereby depression of the other end of any of said keys elevates said one end of the corresponding pallet to open its associated port, means to restore each of said pallets upon release of its respective key, and de-

vices for individually restoring said keys upon release thereof.

9. The combination set forth in claim 8, wherein said key restoring devices comprise springs anchored to said key frame and respectively attached to said keys.

10. The combination set forth in claim 8, wherein said key restoring devices comprise weights carried by said keys.

11. In an air driven reed organ having a plurality of reeds and a wind chest, a series of keys, a corresponding series of pallets having forward portions vertically overlying rear portions of said keys and arranged immediately adjacent the reed cells for respectively controlling the passage of air from said wind chest to said reeds, coupling devices respectively interposed between said rear key portions and said forward pallet portions whereby actuation of a key causes the corresponding pallet to be actuated, means to restore said pallets, and weights carried by said keys for restoring said keys.

12. An electric organ comprising a plurality of sets of electric oscillation generators, electric circuits and sound translating apparatus connected with said generators for producing audible sound therefrom, corresponding generators in said sets producing complete tones of the same pitch but of different quality, each of said generators comprising a vibratory reed, an air pressure source, a set of pitch determination playing keys, means operable by each key for interconnecting the reeds of corresponding generators of the pitch determined by said key with said pressure source for simultaneous vibration thereby, and means for selectively electrically activating certain only of said sets of generators, whereby the operation of a key produces a tone only from those corresponding generators associated therewith which are in sets of generators electrically activated by said selective activating means.

13. An electric organ comprising a plurality of sets of electric oscillation generators, electric circuits and sound translating apparatus connected with said generators for producing audible sound therefrom, corresponding generators in said sets producing complete tones of the same pitch but of different quality, each of said generators comprising a vibratory reed, an air pressure source, a set of pitch determination playing keys, means operable by each key for interconnecting the reeds of corresponding generators of the pitch determined by said key with said pressure source for simultaneous vibration thereby, a source of electric potential, and activating means for selectively interconnecting certain only of said sets of generators with said source of potential, whereby the operation of a key produces a tone only from those corresponding generators associated therewith which are in sets of generators electrically

activated by said selective interconnecting means.

14. An electric organ comprising a plurality of sets of electric oscillation generators, electric circuits and sound translating apparatus connected with said generators for producing audible sound therefrom, corresponding generators in said sets producing complete tones of the same pitch but of different quality, each of said generators comprising a vibratory reed, an air pressure source, a plurality of valve pallets interconnecting with said source, there being one pallet for the reeds of corresponding generators in said generator sets, a set of pitch determination playing keys, means operable by each key for operating a pallet to thereby effect the simultaneous vibration of the reeds corresponding therewith, and means for selectively electrically activating certain only of said sets of generators, whereby the operation of a key produces a tone only from those corresponding generators associated therewith which are in sets of generators electrically activated by said selective activating means.

15. An electric organ as defined in claim 12, wherein said selective activating means for activating the generators comprises a plurality of switch circuits, and a plurality of stop tablets operable respectively to control said switch circuits.

16. An electric organ as defined in claim 12, wherein each of said electric generators comprises in addition to its reed, a pick-up screw juxtaposed to the reed and adjustable in respect thereto.

17. An electric organ as defined in claim 14, wherein said air pressure source comprises a wind chest along which said valve pallets are mounted, and wherein the reeds of corresponding generators are mounted on an air chamber, there being one such air chamber for each valve pallet.

18. An electric organ as defined in claim 14, wherein each of said playing keys is mounted in juxtaposition to its corresponding valve pallet, each pallet being directly mechanically actuated by its corresponding key.
